UNITED STATES PATENT OFFICE.

WILLIAM S. ATWOOD AND FRANK DITCHFIELD, OF MONTREAL, QUEBEC, CANADA.

RAILWAY-CAR.

1,125,832.

Specification of Letters Patent.

Patented Jan. 26, 1915.

Application filed July 11, 1910. Serial No. 571,327.

To all whom it may concern:

Be it known that we, WILLIAM S. ATWOOD and FRANK DITCHFIELD, of the city of Montreal, in the Province of Quebec and Dominion of Canada, have invented certain new and useful Improvements in Railway-Cars, of which the following is a full, clear, and exact description.

This invention relates to railway cars and is particularly adapted to be used in the construction of metallic freight or box cars, although several features of construction may be adapted for use in the construction of passenger cars.

The object is to provide a car that can be properly ventilated at all times without subjecting the interior to drafts, and without liability of leakage through the ventilating apertures.

The invention consists essentially of a car having an underframe of the usual type but having its sides, ends and roof consisting of sheet metal plates, said plates being provided at intervals with vertical integral ribs or corrugations and being so constructed and arranged that continuous ventilating flues or conduits are provided which extend from the bottom of the sides upwardly to the roof, said flues being provided on the interior of the car with suitable apertures for admitting air to the interior thereof. By this means, the ribs form vertical strengthening members or stakes for the sides of the car, said ribs at the same time comprising ventilating flues which prevent the interior of the car from sweating or becoming damp.

In the accompanying drawings which illustrate our invention and in which similar numerals of reference refer to similar parts thereof:—Figure 1 is a partial side elevation of a car constructed according to our invention. Fig. 2 shows, on the left half, a partial plan view, and on the right, a partial horizontal section, on the line 10—11 of Fig. 1. Fig. 3 is an end elevation of the car. Fig. 4 shows, on the left half, a cross section on the line 12—13, and on the right a cross section on the line 14—15, of Fig. 1. Fig. 5 is a partial cross section showing the air flues. Fig. 6 is a detailed cross section of one of the flues. Fig. 7 is a slightly modified form of the flue shown in Fig. 6, adapted for passenger car construction.

Referring more particularly to the parts,

16 designates the center sills, 17 the side sills, 18 the body bolsters, 19 the cross bearers or transoms, 20 the end sills, and 21 the longitudinal floor joists comprising the under-frame of the car and arranged in the usual manner and according to the best approved construction. The floor boards 22 are laid transversely across the joists 21, forming a permanent floor for the car, although it will be obvious that the construction hereinafter described may be used with hopper bottom cars.

The sides, ends and roof of the car are constructed of sheet metal plate, the interior surface being plain and smooth, while the outside of the car has a series of vertical ribs or stakes at intervals along the length thereof, said ribs extending over the roof and being continuous with the sides. These ribs are formed by crimping or corrugating the metal plates of which the upper frame is constructed, the ribs being U-shaped as shown in Figs. 6 and 9, and the edges of the plates being slightly off-set so that the overlapping ends of the adjoining plate may be fitted thereon to form a smooth or plain joint in the interior of the car. The vertical side plates 23 are riveted at the bottom to the angle sections forming the side sills 33 of the car and are riveted at the top to the roof plates. The edges of the plates 23 are off-set as indicated at 24 so that the adjoining plate which overlaps the rib will fit closely without allowing a ridge to project from the surface. The U-shaped ribs 25, formed by corrugating the plates, are of such area in cross section as to permit a large volume of air to circulate therethrough and the plates are overlapped in such a manner as to allow the ribs to run continuously from the bottom of the car to the top and over the roof, the ribs thus constituting ventilating flues. The plates 23 are overlapped, as indicated in Fig. 6, across the ribs and are connected by means of suitable rivets 26 through the flanges on each side of the ribs.

27 designates the end plates of the car.

The transverse roof plates 30 may extend across the car, or may be united at the center of the car and are bent over and downwardly at the sides to connect with the side plates. These roof plates are provided with ribs 31 of the same contour as the ribs 25 on the side plates but slightly larger in order that the ribs 31 will overlap the ribs 25.

forming a tight joint. These ribs 31 form the carlines of the roof and are turned downwardly as indicated at 32. The interior of the roof peak is provided with a longitudinal central air channel 33, which serves not only to brace and unite the roof plates when they are formed in two sections but is further adapted to permit the air from the flues to be distributed through the cars. The roof plates are riveted to the side plates and corner braces 34 to serve further to strengthen the car frame.

Within the ribs or carlines 31, we provide apertures 35 which open into the central air channel 33 and may, if desired, open directly into the interior of the car, as indicated in Fig. 5. Apertures 36 in the air channel 33 permit the air to be distributed from end to end of the car. It will thus be seen that the flues which are open at the bottom will permit air to be drawn upwardly at the sides of the car and distributed evenly at the roof, the side stakes and carlines forming continuous flues for this system of ventilation.

The doorways 42 at the sides of the car are closed by sliding doors 44 somewhat in the usual manner.

For passenger car construction, the ribs 30 are slightly modified in form, the ends 53 being flattened in order to secure same to the outside plate 54. The ribs 25 will, however be similar in other respects, constituting ventilating flues and supports as above described. These flues may be provided with dampers 55 at the bottom, or may be provided with sliding dampers in the interior of the car.

A full description of the remaining structure of the car will be found in our co-pending application, Ser. No. 613,968, divided from this application and filed March 13th, 1911.

It will be seen that this construction of car besides being neat in appearance will be very strong and durable and will be particularly adapted for carrying such freight

as requires ventilation without exposure to rain or moisture. The car is well adapted for carrying live stock and, for this purpose, apertures for the admission of air may be made in the flues at the interior of the sides of the car. For carrying grain, fruit, meat, and the like, this construction of car will eliminate sweating or the accumulation of moisture which is one of the great difficulties heretofore experienced in connection with the use of metal freight cars. It will also be obvious that for passenger cars, this system of ventilation will afford great advantages over any system that can be used in cars of other types.

While we have shown the preferred form of construction, it will be apparent that many modifications may be made without departing from the spirit of our invention.

Having thus described our invention, what we claim is:—

1. In a ventilated car, a series of ventilating flues extending from the lower to the upper edge of the sides, transverse flues connecting the side flues over the roof, said flues being open at their lower ends, a longitudinal flue in the roof connected with said transverse flues, and a plurality of outlets from each transverse flue and from the longitudinal flue.

2. In a ventilated car, a series of ventilating flues extending from the lower to the upper edges of the car sides, a longitudinal flue in the car roof, transverse flues connecting the side flues in pairs with the longitudinal flue, outlets from said longitudinal flue communicating with the interior of the car, and dampers at the lower ends of the side flues.

In witness whereof we have hereunto set our hands in the presence of two witnesses.

WILLIAM S. ATWOOD.
FRANK DITCHFIELD.
